SHOCK ABSORBING PEDESTAL FOR SEATS

Albert M. Kimbro, Houston, Tex.

Application October 7, 1940, Serial No. 360,156

4 Claims. (Cl. 155—52)

The present invention relates to improvements in seats especially designed for motor buses and more particularly to a shock absorbing pedestal for such seats.

The primary object of the invention resides in the provision of means forming a part of a seat supporting pedestal for absorbing the shock occasioned by a motor bus travelling over a rough or uneven highway.

A further object of the invention is to provide a shock absorber of the telescoping cylinder type including the use of a multiplicity of coil springs with means being provided for varying the tension of the springs in accordance with the weight of the user of the seat.

A still further object of the invention resides in the provision of a shock absorber for the seats of buses or the like including a pair of telescoping cylinders, a piston slidably mounted in the upper cylinder and coil springs mounted in the lower and upper cylinders at opposite sides of the piston and separate means adapted to be operated by the user of the seat for varying the tension of certain of the springs held within the cylinders.

The invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a side elevational view of a bus seat supported upon a shock absorbing pedestal embodying the features of the present invention.

Figure 2 is a front elevational view thereof.

Figure 3 is a vertical sectional view through the pedestal with the seat removed therefrom.

Figure 4 is a front elevational view of the pedestal with the seat removed therefrom.

Figure 5 is a horizontal sectional view taken substantially on line 5—5 of Figure 3.

Figure 6 is a top plan view of the pedestal with the seat removed therefrom.

Referring to the drawing for a more detailed description thereof, the two telescoping cylinders are designated by the numerals 8 and 9, the lower cylinder 9 having its end 10 closed and supporting therein a relatively heavy coil spring 11. The lower end of the spring 11 is held within a groove 12 formed in the end 10, while the upper

end of said spring is supported in a slot 13 formed in the lower edge of the cylinder 8. The anchoring of the ends of the spring 11 in the respective cylinders, prevents rotation of said cylinders, movement thereof being limited in a vertical direction. A relatively light weight oil will be confined within the cylinder 9 and maintained at a predetermined level for lubricating the movable parts as well as to decrease the amount of air in said cylinder.

A piston 14 is slidably held within the cylinder 8 and is normally positioned adjacent the lower end of said cylinder as shown in Figure 3. A relatively large opening 15 is formed centrally of the piston 14 and communicates with an aperture 16 formed in the lower end thereof, said aperture being closed by means of a check valve 17. A second aperture 18 is formed vertically of the piston 14 for connecting the upper and lower cylinders. When the two cylinders telescope, air is forced out of the lower cylinder 9 up through the aperture 16 where it is vented through the upper end of the upper cylinder. The aperture 18 acts as a by-pass for allowing the air to return to the lower cylinder as the various parts of the shock absorber assume their balanced position as will hereinafter appear.

The upper end of the cylinder 9 contains a packing 19 of suitable construction which is retained in place by means of the packing nut 20 threadedly attached to said cylinder as indicated at 21. A spring 22 is disposed between the packing and the upper end of the nut 20 for maintaining a proper pressure on the packing thereby alleviating the possibility of the occurrence of a leakage as the cylinders telescope.

The lower end of the cylinder 8 is provided with a circumferentially formed groove 23 adapted to be engaged by the spring pressed dogs 24 carried by the cylinder 9 for preventing separation of the cylinder 8 from the cylinder 9 thereby limiting the upward movement of the former. The spring pressed dogs 24 are held in spaced relation on the cylinder 9 as shown in Figure 5 of the drawing, a cap nut 25 being provided for maintaining the dogs in position.

A feature of the present invention embodies the use of springs 26 and 27 less rigid than the spring 11. The spring 27 is held within the spring 11 and has one end resting against the bottom wall 9 and its other end in engagement with the lower end of the piston 14, while the spring 26 has one end in engagement with the upper face of the piston 14 and its other end in engagement with a cap 28 which is slidably and

adjustably held in the cylinder 8. The cap 28 is formed with vent openings 29 for allowing the escapement of air from said cylinders as the springs are compressed when absorbing a shock. The piston 14 is held in a balanced position between the springs 26 and 27 and is movable vertically by the compression and expansion of said springs.

The upper cylinder 8 has welded or otherwise secured thereto as indicated at 30 a flange plate 31 to which the seat generally designated by the reference numeral 32 is attached. The lower cylinder 9 is likewise provided with a flange plate 33 by means of which said cylinders are attached to the floor 34 of the bus. Bolts or similar means 35 are employed for securing said plate to the floor and it will be observed that the lower end of the cylinder projects below the floor so as to permit the use of a longer spring therein having greater strength. The upper plate 31 is formed with openings 36 through which bolts 37 or similar means extend for attaching the seat 32 thereto.

A means has also been provided for adjusting the tension of the spring 26 and 27 to compensate for difference in the weights of passengers using the seat, said means including a horizontally disposed lever 38 having a crank section 39 formed intermediate its ends, said lever being suitably journaled, as indicated at 40, to the upper face of the flange plate 31. The crank section 39 carries an arm 41 which, upon rotation of the lever 38, depresses the cap 28 to vary the tension on the spring 26 and likewise on the spring 27 since the latter spring is controlled by the action of the piston 14. The lever 38 is held beneath the cushion of the seat 32 and has one end projecting from the front of the seat and on that end is mounted a coil spring 42 which is held under tension sufficient to counterbalance the force exerted on it by the spring 26 in the upper cylinder 8. As is to be understood, one end of the spring 42 is affixed to the plate 31 as indicated at 43 and the other end is suitably anchored to the lever. A U-shaped member 44 having serrations 45 formed on one face thereof is attached to the upper face of the plate 31 above the lever 38, the serrated portion adapted to be engaged by a pin 46 carried by the lever 38 for retaining said lever in adjusted position. When desiring to vary the tension on the springs 26 and 27, the lever 38 is revolved so that the arm 41 will urge the cap 28 downwardly compressing the spring 26 against the piston 14. The position of the piston 14 may vary due to its downward pressure on the spring 27 and thus both of said springs will be under additional compression. The springs will be held in the compressed position including the cap 28 when the pin 46 engages the member 44 and all parts will be held in this position until manually moved.

When the seat is in use, the cylinder 8 will telescope within the cylinder 9 against tension of the springs 26 and 27 until said springs balance the weight of the passenger. When a shock is transmitted upward by the base it is absorbed by all of the springs thus slightly depressing them from their balanced position. The sliding piston 14 prevents the springs 26 and 27 from suddenly springing back to their original position. As the cylinders telescope and the springs are compressed, air is forced out of the lower cylinder 9 through the aperture 16 and out of the upper cylinder through the vents 29

and as the two cylinders start back to their normal balanced position, a partial vacuum will be formed in the lower cylinder because of the position of the check valve 17. This vacuum will retard the upward action of the piston and will maintain some of the tension in the lower spring 27. The upper spring 26 will lose some of its tension because of the piston being held back by the vacuum created. The aperture 18 in the piston 14 acts as a by-pass allowing the air to come back into the lower chamber as the springs, the piston and the cylinders resume their balanced state. With oil or similar fluid in the lower cylinder, a vacuum will be created the instant that the piston starts to return to its normal position. Thus the shock absorber in accordance with the present invention will effectively cushion and absorb various shocks and is prevented from a rapid return to normal position by the action of the vacuum created in the cylinder.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the present invention nor exceed the scope thereof as expressed in the appended claims.

What is claimed is:

1. In a shock absorbing pedestal, a lower cylinder closed at the bottom end and adapted to be mounted in fixed position, an upper cylinder closed at the top and having its lower portion slidably fitted within the upper portion of the lower cylinder, a coil spring mounted in the lower cylinder and engaging the bottom edge of the upper cylinder to yieldingly support the latter, the lower portion of the said upper cylinder having an annular groove formed therein, and a plurality of spring pressed dogs mounted radially on the upper portion of the lower cylinder operative to limit the upward movement of the said upper cylinder.

2. In a shock absorbing pedestal, a lower cylinder closed at the bottom end and adapted to be mounted in fixed position, an upper cylinder closed at the top and having its lower portion slidably fitted within the upper portion of the lower cylinder, a coil spring mounted in the lower cylinder and engaging the bottom edge of the upper cylinder to yieldingly support the latter, the lower portion of the said upper cylinder having an annular groove formed therein, a piston slidably mounted within the upper cylinder having a bore of relatively large diameter formed axially therethrough and a bore of smaller diameter parallel with the said larger bore, a check valve member mounted to prevent downward movement of fluid through the larger bore of the said piston, a coil spring disposed between the bottom of the piston and the closed bottom of the lower cylinder, and a second coiled spring mounted between the top of the piston and the closed top of the upper cylinder.

3. In a shock absorbing pedestal, a lower fixed cylinder closed at the bottom end, an upper cylinder having its lower open end portion slidably fitted within the upper portion of the lower

cylinder, a coiled spring resting on the bottom end of the lower cylinder and engaging the bottom open end of the upper cylinder to yieldingly support the latter, a piston slidably mounted in the said upper cylinder, the said piston having an axial bore of relatively large diameter and a parallel bore of reduced diameter therethrough, a ball check valve operative to preclude downward movement of fluid through the larger bore through the said piston, an apertured cap slidably fitted in the upper portion of the upper cylinder, a coil spring resting on the bottom of the lower cylinder and engaging the bottom face of the piston, an upper coil spring disposed between the top face of the piston and the axially slidable cap in the upper portion of the upper cylinder, and manually operative mechanism for axially sliding the said cap for varying the compression of the said piston contacting springs.

4. In a shock absorbing pedestal, a lower fixed cylinder closed at the bottom end, an upper cylinder having its lower open end portion slidably fitted within the upper portion of the lower

cylinder, a coiled spring resting on the bottom end of the lower cylinder and engaging the bottom open end of the upper cylinder to yieldingly support the latter, a piston slidably mounted in the said upper cylinder, the said piston having an axial bore of relatively large diameter and a parallel bore of reduced diameter therethrough, a ball check valve operative to preclude downward movement of fluid through the larger bore through the said piston, an apertured cap slidably fitted in the upper portion of the upper cylinder, a coil spring resting on the bottom of the lower cylinder and engaging the bottom face of the piston, an upper coil spring disposed between the top face of the piston and the axially slidable cap in the upper portion of the upper cylinder, a seat supporting member mounted on the upper end of the said upper cylinder, and a lever rotatably supported on the said seat supporting member and connected with the said cap for selectively sliding the cap to vary the compression of the piston engaging springs.

ALBERT M. KIMBRO.
